(57) **CLAIM**

The ornamental design for a modular seat, as shown and described.

DESCRIPTION

FIG. 1 is a front perspective view of a modular seat, showing my new design;

FIG. 2 is a top plan view thereof;

FIG. 3 is a right-side elevation view thereof, the left-side elevation view being a mirror image thereof;

FIG. 4 is a front elevation view thereof;

FIG. 5 is a rear elevation view thereof;

FIG. 6 is a perspective view of the modular seat of FIG. 1, showing the top portion of the seat in the middle position; and,

FIG. 7 is a perspective view of the modular seat of FIG. 1, showing the top portion of the seat in the lowest position. The dot-dash-dot broken lines shown in the drawings depict the bounds of the modular seat that form no part of the claimed design.
